Application filed March 7, 1889. Serial No. 302,348. Term of patent 3½ years.

To all whom it may concern:

Be it known that I, JAMES L. FOLSOM, a citizen of the United States, residing in Brooklyn, county of Kings, and State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design is composed of a body, A, and a border, B. The body A is made up of ornamental figures resembling conventionalized water-lily forms. The interstices contain small 20 ornamental work. The border B has a wide inner band composed of similar figures resembling conventionalized water-lily forms.

The inner margin contains gem-shaped figures. The outer band contains a few large fan-shaped figures. Between the outer and 25 inner band is a band containing a few of the conventionalized water-lily forms, and between these an ornamental groundwork. The outer margin of this band is formed by a succession of scroll-shaped figures, and the inner 30 margin is made up of small ornamental figures.

What I claim as new, and desire to secure by Letters Patent, is—

1. The design for carpets, consisting of the body A, substantially as shown. 35
2. The design for carpets, consisting of the border B, substantially as shown.
3. The design for carpets, consisting of the body A and the border B, substantially as shown.
